Patented Apr. 30, 1912.

UNITED STATES PATENT OFFICE.

EDWARD BIGNELL, OF LINCOLN, NEBRASKA.

CAISSON CONSTRUCTION.

1,024,821.

Specification of Letters Patent. Patented Apr. 30, 1912.

Application filed July 31, 1911. Serial No. 641,609.

To all whom it may concern:

Be it known that I, EDWARD BIGNELL, a citizen of the United States, residing at Lincoln, in the county of Lancaster and State of Nebraska, have invented certain new and useful Improvements in Caisson Construction, of which the following is a specification.

This invention relates to improvements in 10 caisson construction, and has for its object, broadly, to provide caissons which may be constructed economically, and which will be fully operative for all of the purposes for which they are generally used.

15 One of the objects of the invention is to provide a construction whereby the caisson will be "self-sinking," and may be lowered or sunk without the presence of workmen below the surface of the ground.

20 Another object is to provide cylindrical caissons of any desired length or diameter which may be lowered or sunk quickly, or without undue loss of time, and with less expense for labor than usual.

25 The herein described caisson is particularly adapted for use in ordinary silt deposits, sand, gravel, clay or any other soil where boulders or like obstructions are not likely to be encountered.

30 With the above objects in view and others hereinafter mentioned, the invention consists of the novel construction, combination and arrangement of parts as described herein and claimed, and as illustrated in the

35 drawing, it being understood that changes in form, size, proportion and minor details may be made within the scope of the claims, without departing from the spirit of the invention or sacrificing any of its advantages.

40 In the accompanying drawing, which illustrates one embodiment of my invention, Figure 1 is a vertical longitudinal section of a caisson, taken on line *a a* of Fig. 2, parts being broken away to more clearly show 45 construction. Fig. 2 is a plan view of the caisson, being a transverse section on line *b b* of Fig. 1. Fig. 3 is a transverse section on line *c c* of Fig. 1. Fig. 4 is a detail relating to Fig. 1, showing a passage- 50 way through the operating wheel.

Referring now to the drawing for a more 55 particular description, the body of the caisson consists, principally, of two cylindrical receptacles, 4 and 5, which may be constructed to advantage of sheet metal, their

side walls and bottoms being respectively indicated at *d* and *e*.

Receptacle 5 has a less diameter than receptacle 4, and is disposed therein to provide the annular chambers 6, 7 and 8 between walls *d* and separated by partitions 9.

At 10 are indicated braces disposed transversely of the annular chambers, between walls *d*, and between the bottoms of the receptacles, so that they may be spaced apart uniformly, or substantially so. The braces and partitions operate to strengthen the caisson so that it may sustain stresses, strains or lateral pressure.

While I have described three annular 70 chambers I may employ more or less, and the number of chambers will depend upon the length or diameter of the caisson, and these dimensions may be varied, also the chambers may have any suitable width.

At 11, near the bottom and within the inner receptacle 5, and secured thereto in any suitable manner, is indicated a transverse supporting-bar or brace having a collar 12, and a similar bar or brace 13 may be 80 employed at the upper end of the caisson.

At 14 is indicated a tubular shaft disposed at the middle of the caisson and suitably journaled in bars 11 and 13, its collar 15 being supported upon collar 12 of bar 11; and 85 rollers or balls 16 may be employed between these collars, if desired, so that the shaft may rotate without undue friction.

Since the shaft traverses walls or bottoms 90 *e*, suitable apertures 17 are provided in these parts for this purpose. Disposed below the caisson and rigidly mounted upon the shaft is the cone-shaped, hollow drill-head 18. It should have a diameter somewhat greater than that of the caisson, and 95 its downwardly convergent wall is formed with numerous perforations 19 and is provided with ridges or fins 20.

Upon the upper terminal of the shaft is mounted the operating wheel 21 which may 100 be actuated by any suitable means to cause a rotation of the drill-head. Any suitable means may be provided so that air or water under pressure may be discharged from the stationary supply pipe 22 within the tubular shaft 14, the means herein shown being the usual apertured ball 23 rigidly mounted upon the pipe and seated in socket 24, the socket being formed in platform 25, this platform being mounted upon the upper 105 110

face of wheel 21, these parts providing a continuous passageway through the ball and wheel.

In practice, water is a better element than air. If the caisson is disposed vertically with the drill-head engaging the ground, and water under pressure be passed within pipe 22 from any suitable source of supply, the water will be discharged through terminal *f* of the pipe within the drill-head and may escape through perforations 19. At this time the drill-head should be rotating; the soil will be loosened by operation of fins 20, and will move with the water in directions of the least resistance, and the caisson will sink into the excavation formed by the drill-head, the soil and water passing upwardly at the outer sides of the caisson in directions indicated by the arrows.

20 To resist the upward pressure of the tubular shaft, during operation, collars 27 may be keyed upon the shaft, these collars being disposed adjacent to and below supporting-bars 11 and 13.

25 To facilitate the upward movement of the soil while the caisson is sinking, and to the end that the soil which has been excavated may be elevated, certain devices are employed now to be described. At 28 are indicated a plurality of supply pipes which are disposed between the outer and inner receptacles and they traverse partitions 9. Their discharge terminals are indicated at *g*, within the lower section or chamber 8.

30 The side wall and bottom of the outer receptacle 4 is formed with numerous perforations *h*. Any suitable number of pipes 28 may be employed and water under pressure, when discharged into chamber 8, will pass through the perforations *h* of the bottom of the outer receptacle and through perforations *h* of the outer wall of chamber 8, and in operation, the water moving in a direction of the least resistance will cause the sand, gravel or other soil which has been excavated to move upwardly.

35 After the caisson has been lowered somewhat farther, additional pipes may be employed, as pipes 29. These pipes may contain water under pressure and their discharge terminals are indicated at *k* within chamber 7. Their function is the same as already described. The water will move outwardly of chamber 7 through perforations *h* of the outer wall of said chamber to cause the excavated soil to move in a direction of the least resistance, or upwardly.

40 The pressure of a liquid or fluid in the several pipes should be under separate control, and for this purpose any suitable devices may be employed, as valves 30. Since the soil to be excavated may be hard or soft, the required pressure in the pipes will vary, the movement of the liquid or fluid through pipes 28 and 29 and perforations *h* of the

sections or chambers being simply to prevent adhesions of the soil to the receptacle, and to convey the gravel or soil upwardly while the caisson is lowered into the excavation.

45 It is understood that, unless packing is employed for the shaft in apertures 17 of the bottoms of the receptacles, water may pass into the inner receptacles, but the gradual filling of the inner receptacles from this source is not objectionable since it overcomes buoyancy, and therefore indirectly aids in the downward movement of the caisson.

50 After the caisson has been sunk to the required depth, certain of the parts or devices mentioned may be removed from the caisson and cement or other heavy filling material may be deposited therein to provide weight and solidity to the structure.

55 While the herein described caisson may be operated to best advantage by use of the drill-head, and its employment is generally preferred, I do not limit myself to its use, for, in some instances, and especially where the caisson is to be sunk in sand bars or soft soils, it may be dispensed with.

Having fully described the several parts, any further explanation relating to operation is not necessary.

What I claim and desire to secure by Letters Patent is,—

1. A caisson comprising an upright, elongated receptacle; a rotatable, tubular shaft longitudinally traversing the receptacle; a hollow drill-head having a perforated wall disposed below the receptacle and mounted upon the shaft; said tubular shaft and drill-head forming a conduit for the passage therethrough of a liquid element.

2. A caisson comprising an elongated, outer receptacle formed at longitudinal intervals with perforations, an elongated receptacle disposed within the perforated receptacle and forming therebetween an annular chamber; tubular members disposed in said chamber to provide conduits for the passage therein of a liquid element, a rotatable tubular shaft longitudinally traversing said receptacle; a hollow drill-head having a perforated wall disposed below the outer receptacle and mounted upon the shaft; said tubular shaft and drill-head providing a conduit for the passage therethrough of a liquid element.

3. A caisson comprising an upright, cylindrical receptacle, a rotatable tube disposed within and extending through the bottom thereof; a hollow drill-head formed with a perforated wall rigidly mounted upon said tube and disposed below the receptacle, said tube and drill-head providing a passageway for a fluid element.

4. A caisson comprising an upright, cylindrical receptacle provided upon its inner wall with transversely disposed sup-

- porting-bars; a tubular member longitudinally traversing the receptacle and journaled in the supporting-bars, said tubular member having a discharge port below the 5 bottom of the receptacle and providing a passageway for a fluid element.
5. A caisson comprising a cylindrical, outer receptacle formed at longitudinal intervals with perforations, a cylindrical receptacle provided upon its inner wall with supporting-bars and disposed within the perforated receptacle to form a chamber therebetween; tubular members disposed in said chamber to provide conduits for the 10 passage therein of a fluid element; a rotatable shaft longitudinally traversing the receptacles and journaled in the supporting-bars; a hollow drill-head having a tapered perforated wall, said drill-head being disposed below the outer receptacle and mounted upon the shaft; said shaft and drill-head providing a passageway for a fluid element.
6. An improvement in caisson construction, comprising an outer, elongated receptacle formed with perforations in its bottom and side walls; a second elongated receptacle disposed within the outer receptacle, a plurality of partitions disposed transversely at longitudinal intervals of and 15 between the receptacles to form chambers; and a plurality of conducting pipes having discharge ports disposed within and adapted to convey a liquid element to said chambers.
7. An improvement in caisson construction, comprising an outer, upright cylindrical receptacle formed with perforations in its bottom and side walls; a second, upright, cylindrical receptacle disposed within 20 the outer receptacle, a plurality of partitions disposed transversely at longitudinal intervals of and between the receptacles to form chambers; a plurality of conducting pipes having discharge ports disposed within and adapted to convey a liquid element to said chambers; a tubular shaft provided at one 25 of its terminals with a cone-shaped hollow drill-head with perforations in its tapered wall, said shaft being disposed substantially in the axial plane and traversing said receptacles with its drill-head disposed below the bottom of the outer receptacle, said shaft and drill-head providing a conduit for the passage therethrough of a liquid element.

at one of its terminals with a discharge port and a drill-head, said shaft longitudinally traversing the receptacles and being disposed substantially in the axial plane 50 with its drill-head and discharge port below the bottom of the outer receptacle for conveying a liquid element.

8. An improvement in caisson construction, comprising a cylindrical receptacle 55 formed with perforations in its bottom and side walls; a second cylindrical receptacle disposed within the outer receptacle, a plurality of partitions disposed transversely between the receptacles to form a plurality 60 of chambers; and a plurality of conducting pipes adapted to convey a liquid element, said pipes having their discharge ports disposed within said chambers.

9. An improvement in caissons, comprising, in combination with an outer, upright cylindrical receptacle formed with perforations in its bottom and side walls; a second, upright cylindrical receptacle disposed within the outer receptacle, a plurality of 65 partitions disposed transversely between the receptacles to form a plurality of chambers; a plurality of conducting pipes adapted to convey a liquid element and having their discharge ports disposed within said 70 chambers; a tubular shaft provided at one of its terminals with a cone-shaped hollow drill-head with perforations in its tapered wall, said shaft being disposed substantially in the axial plane and traversing said receptacles with its drill-head disposed below the bottom of the outer receptacle, said shaft and drill-head providing a conduit for the passage therethrough of a liquid element. 80

In testimony whereof I have affixed my signature in presence of two witnesses.

EDWARD BIGNELL.
